UNITED STATES PATENT OFFICE.

RUDOLF DERRER, OF RUTI, SWITZERLAND, ASSIGNOR TO MASCHINENFABRIK RÜTI
FORMERLY CASPAR HONEGGER, OF RUTI, ZURICH, SWITZERLAND.

DEVICE FOR RELEASABLY LOCKING THE LOOSE REEDS OF POWER LOOMS.

Application filed April 5, 1922. Serial No. 549,764.

To all whom it may concern:

Be it known that I, RUDOLF DERRER, a citizen of the Republic of Switzerland, residing at Ruti, Canton of Zurich, Republic of Switzerland, have invented certain new and useful Improvements in Devices for Releasably Locking the Loose Reeds of Power Looms, of which the following is a specification.

10 In power looms with a fixable, loose reed the latter is fixed or locked, when the shuttle is in normal operation, just before the beat of the reed, for beating up the weft. On the shuttle getting stuck in the warp, the 15 loose reed swings backwards, so that the warp threads shall not be liable to be torn by the beating up of the lay. In this case the reed will not be locked with the lay.

For locking the loose reed a bar adapted 20 to slide along the lay is generally used (see for instance German Patent 63172), which bar in the operative position locks a pivoted member, which presses resiliently against the lower edge of the reed, to the lay, so that, 25 when the shuttle operates normally, the beat of the reed will take place in the proper manner. The loose reed is released at the commencement of the forward movement of the lay, by a cam which is brought by the 30 crank shaft and a lever within range of a bolt attached to the locking bar, whereby the latter is displaced into the inoperative position. Should a shuttle get stuck in the warp during the forward movement of the 35 lay, when the reed is not locked, it will swing the loose reed backwards, thus preventing the warp threads from being torn. In this case there will be no locking of the reed with the lay just before the end of the forward 40 movement of the latter.

One disadvantage of the above means for the positive displacement of the locking bar resides in the fact, that the co-action of parts, that move to and fro with the lay, and 45 other stationary ones, that are mounted on the frame of the loom and are operated from the crank shaft independently, gives rise to trouble and makes the entire arrangement inconvenient. The friction of the stop-pin 50 of the locking bar will cause considerable wear on the cam.

In the device according to the invention, in which for locking the reed with the lay a reciprocating locking bar and a clamping 55 bar for the reed, which is adapted to be

coupled with the locking bar by at least one member passing transversely through the lay, are used, the disadvantages mentioned above are overcome, by all the parts required for operating the locking bar being 60 mounted on the lay and the positively controlled displacement of the locking bar being derived through intermediate members from the oscillating motions of one of the pitmans imparting a swinging motion to the 65 lay. Smooth working with very little frictional resistance and great constructional simplicity are the main advantages of the invention.

The accompanying drawing shows a constructional example of the device according 70 to the invention.

Fig. 1 is a side elevation of the lay showing the crank shaft and the pitmans diagrammatically;

Fig. 2 is a partial front elevation of the 75 lay;

Fig. 3 is a cross-section through the lay and the locked reed;

Fig. 4 is a partial plan view of the lay 80 with the reed in the locked position;

Fig. 5 is a cross-section through the lay with the reed released and thrown back and

Fig. 6 is a partial plan view of the lay 85 with the reed released and thrown back.

1 (Fig. 1) is the crank shaft of a power loom, in which the two pitmans 2 impart a swinging motion to the lay 4, which is supported by the lay sword 3. The front end of one of the pitmans 2 is mounted on 90 a front pin 6, which is rotatably journaled in the adjacent lay sword 3 in bearings 5, and on which pin a lever 7 with a hook-shaped end is also mounted. This sleeve-shaped end is provided with a pin 8, on 95 which a crowned roller 8' is loosely mounted. The forked end of the horizontal arm of the bell-crank lever 9, 11, embraces the said roller. The bell crank lever 9, 11 is pivoted at 10 on the lay and the vertical 100 arm of this lever carries a pin upon which a roller 11' is loosely mounted. The lever 9, 11 is perpendicular to the lever 7.

On the front of the lay the usual locking bar 12 is slidably mounted. It carries a 105 bent tappet 13 and a plate 14, which is provided with a locking projecting part 15 of semi-circular cross-section and a bearing 16 for a sliding pin 17 with a head 18. Between the head 18 and the bearing 16 a 110

compression spring 19 is mounted on the pin 17, which spring seeks to force the locking bar 12 to the left and the head 18 of the pin against the roller 11' at the unsupported end of the vertical arm 11 of the bell-crank lever 9, 11. (See Fig. 2.) The spring 19 also forces the bent tappet 13 against the roller 11'.

The reed 21 is mounted so as to swing in the hand rail 20. The swinging clamping bar 22 presses the reed 21 by means of a spring, which is not shown, resiliently against the lay 4 and is provided over its entire length with a number of locking bolts 23, which pass through transverse holes in the lay 4 and of which only one is shown in the drawing. Each bolt 23 is provided with a nut 24 having an integral flange 25 and with a lock nut 26 and is pivoted to 20 the clamping bar 22.

The operation of the above described apparatus is as follows:—

When, after the shuttle has run right into the shuttle box, the pitmans 2 swing the lay forward, one of the said pitmans moves the levers 7 and 9, 11 in such a manner that the roller 11' of the upright arm 11 forces the pin 17 to the right (Figs. 2 and 4), and that the spring 19 is compressed and the locking bar 12 is pushed to the right. The semicylindrical projecting piece 15 passes behind the flange 25 of the nut 24 (Figs. 2, 3 and 4), causing the reed 21 to be locked to the lay and made ready for beating up. On the lay moving backward, the levers 7 and 9, 11 are moved in the opposite direction by the corresponding pitman 2 and the roller 11' of the arm 11 of the bell-crank lever, will press against the bent tappet 13, by which means 40 the reed 21 is released.

Should a shuttle 27 (Fig. 5) get stuck in the warp, it will, when the lay 4 moves forward, press back the reed 21 and the reed will press back the reed clamping bar 22 with the bolts 23 (Figs. 5 and 6) so that the projecting piece 15 will not pass behind the flange 25 of the nut 24 and thus the reed cannot be locked. When the lever 9, 11 is now moved in the clockwise direction 50 the spring 19 is compressed without imparting movement to the locking bar 12 (Fig. 6). The roller 11' is now moved from the tappet 13. As soon as the reed when pushed back by the shuttle releases the reed clamping bar 55 22, the latter will again swing forward into its starting position without locking taking place, however.

Owing to the rolling movement of the lever 7 on the lever 9, 11 and that of the roller 11' on the head 18 of the pin and the bent tappet 13 the friction and wear is very small. The construction of the entire loose reed arrangement is exceedingly simple and is therefore never likely to get out of order.

65 The locking motion of the locking bar

can be effected by a tension spring, instead of by a compression spring.

What I claim is:

1. In a power loom, in combination, a lay, means for oscillating the lay including a plurality of pitmans, a loose reed capable of being locked, a reciprocating bar on the lay, a pivotally mounted bar for clamping the loose reed to the lay, bolts carried by the clamping bar and passing transversely through the lay for coupling the clamping bar to the lay, means carried by the reciprocating bar and cooperating with the bolts to secure the same in the coupling position, a spring acting upon the reciprocating bar and the said securing means, and means between the said spring and one of the pitmans to reciprocate the bar in opposite directions, substantially as and for the purposes set forth.

2. In a power loom, in combination, a lay, means for oscillating the lay including a plurality of pitmans, a loose reed capable of being locked, a reciprocating bar on the lay, a pivotally mounted bar for clamping the loose reed to the lay, bolts carried by the clamping bar and passing transversely through the lay for coupling the clamping bar to the lay, means carried by the reciprocating bar and cooperating with the bolts to secure the same in the coupling position, a spring acting upon the reciprocating bar and the said securing means, and a pair of levers arranged in crossed relation between the said spring and one of the pitmans and capable of rolling on each other to reciprocate the bar in opposite directions substantially as and for the purposes set forth.

3. In a power loom, in combination, a lay, pitmans for swinging the lay, a loose reed capable of being locked, a reciprocating locking bar on the lay, a clamping bar for clamping the loose reed to the lay, bolts carried by the clamping bar passing transversely through the lay for coupling the clamping bar to the lay, nuts on the bolts, projections extending from the locking bar and engageable at times behind the nuts, a bell crank lever pivoted to the lay to reciprocate the locking bar, a spring exerting a resilient pressure on the bell-crank lever in one direction and means for operably connecting the bell-crank lever to one of the pitmans for controlling the displacement of the locking bar from the said pitman.

4. In a power loom, in combination, a lay, pitmans for swinging the lay, a loose reed capable of being locked, a reciprocating locking bar on the lay, a clamping bar for clamping the loose reed to the lay, bolts carried by the clamping bar and passing transversely through the lay for coupling the clamping bar to the lay, nuts on the bolts, projections extending from the locking bar and engageable at times behind said nuts, a

bell-crank lever pivoted to the lay to reciprocate the locking bar, a roller mounted on one arm of the lever to act upon the locking bar and the other arm being bifurcated at the 5 outer end thereof, a spring exerting a resilient pressure on said roller upon the locking bar in one direction, another lever operably connected to one of said pitmans and having a hook-shaped outer end, a roller mounted in 10 the hook-shaped lever and engaged by the bifurcated arm of the bell-crank lever, and both of said levers being substantially perpendicular one to the other and capable of rolling on each other, substantially as and 15 for the purposes set forth.

5. In a power loom, in combination, a lay, pitmans for oscillating the lay, a loose reed capable of being locked, a reciprocating locking bar on the lay, a clamping bar for 20 clamping the loose reed to the lay, bolts carried by the clamping bar and passing transversely through the lay for coupling the clamping bar to the lay, nuts on said bolts, 25 projections extending from the locking bar and engageable behind nuts on the said bolts, a bell-crank lever pivoted to the lay to

reciprocate the locking bar, a roller mounted on one arm of the lever and the other arm being bifurcated at the outer end thereof, a 30 spring exerting a resilient pressure on the roller in one direction, a bearing carried by the locking bar, a pin slidably mounted in said bearing and having a head, the spring being arranged on the pin between the head and the bearing, the pin being arranged to 35 receive the pressure of the roller to compress the spring without moving the locking bar in the event the said projections on the locking bar are not engaged behind the nuts, another lever operably connected to the front 40 end of one of said pitmans and having a hook-shaped end, another roller mounted in said hook-shaped lever and engaged by the bifurcated arm of the bell crank lever, and both of said levers being substantially perpendicular one to the other and capable of 45 rolling on each other, substantially as and for the purposes set forth.

In testimony whereof I have affixed my signature.

RUDOLF DERRER.
